Specification for Design.

Patented Dec. 9, 1919.

Application filed September 26, 1919. Serial No. 326,686. Term of patent 14 years.

To all whom it may concern:

Be it known that I, FRANK H. BREWSTER, a citizen of the United States, residing at Buffalo, in the county of Erie and State of New York, have invented a new, original, and ornamental Design for Tire-Casings, of which the following is a specification, reference being had to the accompanying drawing, forming part thereof.

In the drawing,—

Figure 1 is a plan view of a section of the tread of a tire embodying the features of the present invention.

Fig. 2 is a transverse section therethrough.

I claim:—

The ornamental design for a tire casing, as shown.
